PATRICK O'THAYNE, OF NEW YORK, N. Y., ASSIGNOR TO HIMSELF
AND D. W. CANFIELD, OF THE SAME PLACE.

Letters Patent No. 85,845, dated January 12, 1869.

IMPROVED CURTAIN-FIXTURE.

The Schedule referred to in these Letters Patent and making part of the same.

To all whom it may concern:

Be it known that I, PATRICK O'THAYNE, of New York, in the county of New York, and State of New York, have invented a new and improved Window-Shade Fixture; and I do hereby declare that the following is a full, clear, and exact description thereof, which will enable others skilled in the art to make and use the same, reference being had to the accompanying drawings, forming part of this specification, in which—

Figure 1 represents a transverse section of my improved window-shade fixture.

Figure 2 is a side view of the sliding portion of the same.

Similar letters of reference indicate like parts.

This invention relates to certain improvements on the window-shade fixture for which an application for a patent was filed on the 26th day of October, by Patrick O'Thayne and D. W. Canfield.

The object of the present improvement is to avoid the clamping of the screw against the back of the main plate, whereby, in the aforesaid application, the slide was fastened. In the present case, the clamping is done against both sides of the flanges or guides, formed on the main plate, by means of a recessed nut on the screw-handle, and by a shoulder on the screw. The clamping will thereby be more reliable than by the screw alone, and will not tend to injure the main plate.

A, in the drawing, represents the main plate of the fixture.

It is made of sheet-metal, or other suitable material, and is provided with flanges or guides, *a a*, at the sides, as usual.

B is the slide working on the guides *a*, its sides being grooved to receive the guides, as shown.

C is a screw, with a knob, *b*, at its upper end.

This screw fits with its lower end into the slide or nut B, and has a shoulder, *c*, formed on it.

Where the screw enters the nut, a portion of the latter is cut away, so that the shoulder *c* may be brought directly against the guides *a*, as is clearly shown in fig.

1. The clamping is thus done by the nut B and the shoulder *c* of the screw.

D is the roller for holding the cord. It is put on the outer part of the screw.

Having thus described my invention,

I claim as new, and desire to secure by Letters Patent—

The slide and nut B, provided with a central recess to receive the shoulder *c*, formed upon the screw-knob C, in such a manner that the guides *a a*, of the plate A, shall be clamped between the lower flange of the nut and the shoulder *c*, as herein described, for the purpose specified.

P. O'THAYNE.
